CLAIM

The ornamental design for a remote control, as shown and described.

DESCRIPTION

FIG. 1 is the perspective view of a remote control showing my new design;

FIG. 2 is a rear elevational view thereof;

FIG. 3 is a bottom plan view thereof;

FIG. 4 is a front elevational view thereof;

FIG. 5 is a left side elevation view thereof;

FIG. 6 is a right side elevation view thereof; and,

FIG. 7 is a top plan view thereof.

The broken lines in the figures depict portions of the remote control that form no part of the claimed design.
